(57) **CLAIM**

What is claimed is the ornamental design for a closure, as shown and described.

DESCRIPTION

FIG. 1 is a top perspective view of the closure of FIG. 1. The broken lines are shown to define a boundary around a center portion of an aperture of the closure. The area within the broken lines is not part of the claimed design.

FIG. 2 is a top plan view of the closure of FIG. 1.

FIG. 3 is a left side view of the closure of FIG. 1. The right side view of the closure of FIG. 1. is the mirror image of FIG. 3, not shown.

FIG. 4 is a front elevation view of the closure of FIG. 1.

FIG. 5 is a rear elevation view of the closure of FIG. 1; and, FIG. 6 is a bottom plan view of the closure of FIG. 1. The circular broken lines are shown to define a boundary around a bottom center portion of the closure and a boundary around an aperture of the closure. The area within the broken lines is not part of the claimed design.
